ALLEVIATOR FOR HYDRAULIC APPARATUS

Frank McFarland, Mexico, Mo.

Application September 29, 1930
Serial No. 485,124

1 Claim. (Cl. 103—223)

This invention relates to alleviators for hydraulic pumps, flow lines and other kinds of hydraulic apparatus.

The main object of my invention is to provide a compact and inexpensive alleviator that is particularly adapted for use with large sized pumps and with large sized mains in which a considerable volume of liquid is being pumped.

Another object is to provide a multi-cylinder alleviator in which a single piston or plunger that is arranged in opposed relationship with an expansible means or a shock absorbing medium confined in one cylinder, also acts as a valve or cut off device to control the admission 15 of the pumped liquid to a second or separate cylinder wherein is confined a means or medium that co-acts with the pumped liquid to absorb shocks.

I have herein illustrated my present invention embodied in an alleviator of the general type disclosed in my U. S. Patent No. 1,640,046, dated August 23, 1927, but I wish it to be understood that my broad idea is applicable to various types and kinds of alleviators and that various changes 25 may be made in the construction and arrangement of the parts of the alleviator without departing from the spirit of my invention.

Figure 1 of the drawing is a top plan view of a hydraulic pump equipped with an alleviator embodying my present invention; and

Figure 2 is an enlarged vertical sectional view of said alleviator.

In the drawing, A designates a conventional hydraulic pump that is used for forcing a liquid through a main or flow line, and B designates as an entirety an alleviator for reducing the force of discharge of the liquid being pumped or for maintaining a substantially uniform rate of discharge of liquid from or through the apparatus with which the alleviator is used. In Figure 1 the alleviator B is illustrated as being mounted upon or connected with the discharge pipe 1 of the pump, but it will, of course, be obvious that the alleviator may be arranged in 45 various other positions.

The alleviator B comprises a cylinder C closed at its upper end and provided at its lower end with an opening 2 that establishes communication between the interior of the cylinder and the discharge pipe 1 of the pump, and a reciprocating piston or plunger D is mounted in the cylinder C in such a manner that when a certain approximate pressure develops in the discharge pipe 1, the piston D will move upwardly and 55 compress a shock absorbing means in the upper

portion of the cylinder C which will usually consist of an expansible medium such as compressed air, or compressed air and a body of oil x or other suitable liquid that seals the joint between the side wall of the cylinder C and the coating 60 side wall portion of the piston D. At the lower end of the piston D is a reduced extension 2a that constitutes a dash pot element which enters the opening 2 in the lower end of the cylinder as the piston D nears the end of its downward 65 stroke. Surrounding the dash pot element 2a on the lower end of the piston is a gasket 2b that effectively seals the lower end of the cylinder C when the piston D is at the end of its downward stroke.

The alleviator B also comprises an additional cylinder or second cylinder E whose upper end is closed and whose lower end is connected by a lateral outlet 3 with the cylinder C adjacent the lower end or open end of the cylinder C. When 75 the piston D is in its depressed position, shown in Figure 1, it acts as a valve for the lateral outlet 3 that absolutely cuts off communication between the interior of the cylinder E and the interior of the cylinder C or the pipe 1 through 80 which the pumped liquid is flowing. When the piston D moves upwardly, due to the pressure exerted on same by the pumped liquid, said pumped liquid can enter the lateral outlet 3 leading to the cylinder E.

The cylinder E is provided with a means or medium for absorbing the shock produced by the inrush of the pumped liquid into the cylinder E. Various means may be used for this purpose, but I prefer to charge the cylinder E with 90 compressed air or a similar medium that is capable of being compressed by the pressure exerted on same by the inrushing pumped liquid and thereafter expanding after the shock has been absorbed so as to effect the discharge of 95 the liquid from the cylinder E. In order to facilitate the introduction of the expansible shock absorbing medium into the cylinder E, a compressed air supply pipe 4 equipped with a gage 5 is attached to the cylinder E, as shown in 100 Figure 2.

When the pump A is stopped or shut down the piston D moves downwardly in the cylinder C, thereby closing the connection 3 between the cylinders C and E, and cutting off communication 105 between the interior of the cylinder E and the conduit through which the pumped liquid is flowing. So long as the piston D remains in its depressed position, there is no liability of the expansible medium in the cylinder E escaping 110

from same, due, of course, to the fact that the combined inlet and outlet 3 of the cylinder E is closed tightly by the piston D which acts as a valve or cut-off device. In practice some of the 5 pumped liquid that enters the cylinder E when the piston D moves upwardly, remains in the lateral outlet 3 when said piston returns to its depressed position, and this body of liquid that becomes trapped in the lower portion of the 10 cylinder E or in the connection 3 between the two cylinders serves as a liquid seal for the piston D that absolutely eliminates the possibility of the expansible medium in the cylinder E escaping from same. I prefer to design the alleviator so that the main force of the shock is 15 taken up by the expansible medium confined in the cylinder E, and accordingly, I propose to charge the cylinder E with compressed air whose initial pressure is less than the pressure of the 20 air confined in the upper portion of the cylinder C. The cylinder C and the reciprocating piston D therein are preferably but not necessarily constructed in the manner described in my prior U. S. patent previously referred to.

25 One of the main advantages of my improved alleviator is that it may be designed for use with large sized pumps and with large sized mains in which a considerable volume of liquid is being pumped, without producing a cumbersome and 30 expensive structure, as would be liable to result if the alleviator were provided with a single cylinder containing a shock absorbing means or medium. Another very desirable characteris-

tic of my improved alleviator is that it is practically impossible for an expansible medium confined in the cylinder E to escape therefrom, if the alleviator remains inactive for a long period, thereby insuring that the alleviator will always 80 be in readiness to act and perform the function for which it is designed.

Having thus described my invention, what I 85 claim as new and desire to secure by Letters Patent is:

An alleviator for a liquid pumping apparatus, comprising a primary cylinder having a head or closed end, a plunger in said cylinder that is adapted to be moved towards said head by pressure exerted on same by the liquid being pumped, 90 the portion of the cylinder lying between the end of the plunger and the head of the cylinder being closed to the atmosphere and containing an expansible gas under pressure for opposing the movement of said plunger, a secondary cylinder having a head or closed end and containing a gas that is under sufficient super-atmospheric pressure to constitute a shock-absorbing medium for the pumped liquid, and a connection between 95 said primary cylinder and secondary cylinder arranged so that after the plunger in the primary cylinder has been moved by the pressure of the pumped liquid, said liquid will thereafter enter the secondary cylinder, whereby the shock will be absorbed progressively by the conjoint 100 action of said primary cylinder and secondary cylinder.
